UNITED STATES PATENT OFFICE.

PERRY H. HAMILTON, OF BALTIMORE, MARYLAND, ASSIGNOR TO MAINTENANCE EQUIPMENT COMPANY, OF CHICAGO, ILLINOIS, A CORPORATION OF ILLINOIS.

WHEEL-FLANGE OILER.

Application filed December 17, 1926. Serial No. 155,418.

This invention relates to a wheel flange oiler, and more particularly to a device for delivering oil onto the flange of a car wheel, this oil being in turn delivered by the flange 5 to a switch point, a frog point, a guard rail, or the side of the regular track rail.

A receptacle, holding a certain quantity of oil, is mounted on the rail, at that side thereof where the wheel flange travels. A rotatable roller is yieldingly supported in this receptacle so that its lower portion projects into the bath of oil, and its upper portion projects into the path of travel of the wheel flange. Pawl and ratchet, or equivalent 10 means is provided whereby the roller is caused to rotate when depressed against its yieldable supports. When a car passes thereover, the wheel flange will throw the roller downwardly, thereby causing it to rotate and 15 throw oil upwardly onto the wheel flange. After one revolution, this oil will be delivered to the switch point, or other device where lubrication is required, and the oil receptacle is positioned at such a distance 20 from the switch point to be oiled that the wheel will make approximately one revolution while traveling from one to the other.

The primary object of this invention is to provide a wheel flange oiler, operating as 25 briefly described hereinabove, and as described in more detail in the description which follows:

Another object is to provide improved 30 means for mounting this oiler on the side of the rail.

Another object is to provide such a wheel 35 flange oiler embodying a revolute roller.

Another object is to provide improved 40 means for causing the roller to rotate when depressed into the oil.

Another object is to provide improved 45 means for yieldingly mounting this roller in the oil receptacle.

Another object is to provide improved 50 means for adjusting the roller transversely of the receptacle, that is toward or from the side of the rail head.

Another object is to provide improved 55 means whereby one or more oil delivering rollers may be selectively mounted and spaced within the same oil receptacle.

Other objects and advantages of this invention will be more apparent from the following detailed description of one approved form of the apparatus.

In the accompanying drawings: Fig. 1 is a plan view of the apparatus, mounted on the rail.

Fig. 2 is a transverse vertical section, on an enlarged scale, this view being taken substantially on line 2—2 of Fig. 1.

Fig. 3 is a transverse vertical section, similar to Fig. 2, the view being taken substantially on the line 3—3 of Fig. 1.

Fig. 4 is an end view of the apparatus, mounted on the rail, the rail being shown in transverse vertical section.

Fig. 5 is a side elevation of the apparatus, the oil-delivering roller being shown in normal elevated position.

Fig. 6 is a view similar to Fig. 5, showing the roller being depressed as a wheel passes thereover.

The improved wheel flange oiler comprises an elongated receptacle, closed at its sides 75 and ends, but substantially open at the top, the bottom 1 of the receptacle being preferably shaped to conform to and rest upon one flange 2 of the rail base of a standard railway rail, and one side wall 3 being shaped 80 to rest against the vertical web 4 of the rail, this side wall extending upwardly to approximately the under side of the rail head 5. Side wall 3 terminates in an inturned horizontal flange 6, which functions as hereinafter described. The opposite side wall 7 of the receptacle may be given any desired 85 conformation, but is substantially parallel with the inner side wall 3, and extends upwardly to the level of the lower surface of flange 6. Any suitable means may be used 90 to secure the oil receptacle in place on the rail, as here shown a flange 8 extends from the bottom wall 1 and side wall 3, beyond the end wall 9, and a clamp member 10 is 95 provided for securing this flange 8 to the flange 2 of the rail base. The clamp member 10, as here shown, is similar in construction and operation to a one-piece rail-anchor, for example, the anchor disclosed in 100 the patent to Fair, 1,364,263, granted January 4, 1921. Other forms of clamps might be used, or the flange 8 could be bolted directly to the rail flange 2 or the vertical web 4.

Projecting inwardly from each of the side walls 3 and 7 of the receptacle are a plurality of opposed pairs of guide ribs 11. The vertical passage or guideway 12 between one pair of ribs 11 is directly opposite the guide- 110

way 12 between a pair of ribs 11 on the opposite side wall of the receptacle. The upper ends of the guide-ways 12 adjacent side wall 3 are all closed at their upper ends by the inwardly projecting flange 6, hereinabove referred to. In a similar manner, the open upper ends of the guideways 12 adjacent the opposite side-way 7 may be closed by the inwardly projecting flange 13 of an angle plate, the other downwardly projecting flange 14 of this plate being bolted to the side wall 7, by means of bolts 15, as indicated in Figs. 2, 4 and 5. Thimbles 16 are adapted to slide up and down in the passages 12, and are normally held at the top of those passages in contact with the flanges 6 or 13 by means of supporting springs 17. In the form here shown, each spring 17 comprises a downwardly slanting end portion 18 which engages with the bottom wall of the receptacle, an intermediate coil 19, and an upwardly slanting end portion 20 which projects through a slot 21 in one of the guide ribs 11 and extends beneath the thimble 16 to act as a yielding support therefor. Preferably a pair of similar springs 17 are used to support each thimble 16, these springs projecting inwardly through the two guide ribs 11, in opposite directions. Lugs 22 may project from the adjacent side wall of the receptacle into the coils 19 of the springs to hold the springs in place beneath the thimbles 16. A short horizontal shaft 23 has its end portions journaled in the thimbles 16 for free rotation, and a solid, preferably metallic roller 24 is mounted on the shaft 23. This roller 24 is of such size that when the shaft 23 and thimbles 16 are held up against the stops 6 and 13 by the springs 17, the upper portion of the roller will lie adjacent the head 5 of the rail and in the path of travel of the flange 25 of a car wheel, (see Fig. 6). In order to properly adjust the roller 24 toward or from the rail head 5, a plurality of spacing washers 26 are placed on the shaft 23 at either side of the roller, and between the roller and the ends of the thimbles 16. By varying the number of washers 26 used at either side of the roller, the roller can be adjusted toward or from the rail head, as desired. When in this elevated position, the lower portion of the roller 24 projects downwardly into the bath of oil in the receptacle, but there is sufficient clearance between the roller and the bottom of the receptacle to permit the roller to be depressed, against the resistance of the springs 17, when a car wheel passes therover.

On either one, or both, side faces of the roller 24, a circular series of ratchet teeth 27 is formed and a vertically projecting pawl 29 pivoted at its lower end 30 within the receptacle has its upper end 31 held yieldingly in engagement with the teeth 27 by

means of a spring 32. This spring 32 may be of the coil type here shown, or of any other equivalent or suitable form. It is obvious that the pawl or pawls 29 will permit the roller 24 to rotate freely in one direction, but will prevent rotation in the opposite direction. When the roller 24 is pushed downwardly, or depressed into the oil bath, the engagement of the pawls 29 with the ratchet teeth 27 will enforce a rotation of the roller 24 in a clockwise direction, as shown in Fig. 6.

In operation, as each car wheel passes over the oiling apparatus, the flange 25 of the wheel will strike the roller 24 and throw it downwardly against the resistance of the springs 17, and the pawls 31 by means of their engagement with ratchet teeth 27 will cause the roller 24 to spin within the oil. The sudden depression of the roller 24 will splash oil upwardly onto the flange 25 of the wheel, and the spinning roller will also throw up oil by centrifugal force. When the wheel has passed by, the springs 17 will return the thimbles 16 to their elevated position against the stops 6 and 13, thus raising the roller 24 again into position to be struck by the next car wheel flange. This device, as here shown, will oil about eight inches of the circumference of the wheel flange, which will in turn oil about that much of the track rail one revolution beyond the location of the oiling device. The oil receptacle should, therefore, be located on the track a distance equal to approximately one revolution of the wheel in advance of the track section or switch point which is to be oiled.

A greater distance on the wheel flange may be oiled by placing these rollers in series. In the example here shown, three sets of guide flanges 11 are arranged at spaced intervals in the elongated oil receptacle. When only one oiling roller 24 is to be used, this will ordinarily be positioned in the central sets of guides, as shown in the drawings. If more than one roller is to be used, these additional rollers will be mounted in the other sets of guides, as desired. Each roller and its supporting and operating devices can be assembled in an obvious manner within the guides 12 and then secured in place by the angle stop plates 13, held in place by bolts 15.

As an alternative construction, the ratchet teeth 27 on roller 24 might be oppositely directed, and the pawls 31 mounted at the opposite side of the roller and projecting downwardly into engagement with the ratchet teeth. In this construction, the roller 24 would be rotated when thrown upwardly by the spring 17, after having been depressed by the wheel flange.

I claim:

1. A wheel flange oiler, comprising a re-

ceptacle for oil adapted to be mounted adjacent a rail, and rotatable means yieldingly mounted in the receptacle and projecting upwardly into the path of the wheel flange, whereby it will be depressed and rotated by the flange and throw oil upwardly onto the flange.

2. A wheel flange oiler, comprising a receptacle for oil adapted to be mounted adjacent a rail, rotatable means partially immersed in the oil and normally projecting upwardly into the path of the wheel flange, means for yieldingly supporting the rotatable means in this position, and means for causing the rotatable means to rotate when it is depressed.

3. A wheel flange oiler, comprising a receptacle for oil adapted to be mounted adjacent a rail, a roller mounted on a horizontal axis within the receptacle, means for yieldingly supporting the roller in the path of the wheel flange so that it will be depressed thereby, and means for causing the roller to rotate when it is depressed.

4. A wheel flange oiler, comprising a receptacle for oil adapted to be mounted adjacent a rail, a roller mounted on a horizontal axis within the receptacle, means for yieldingly supporting the roller in the path of the wheel flange so that it will be depressed thereby, a series of ratchet teeth on the roller, and a pawl mounted within the receptacle and held yieldingly in engagement with the ratchet teeth.

5. A wheel flange oiler, comprising a receptacle for oil adapted to be mounted adjacent a rail, substantially vertical guides in the receptacle, a horizontal shaft mounted in the guides, a roller on the shaft, the roller being partially immersed in the oil and projecting upwardly into the path of travel of the wheel flange, and springs for yieldingly supporting the shaft and roller in this position.

6. A wheel flange oiler, comprising a receptacle for oil adapted to be mounted adjacent a rail, substantially vertical guides in the receptacle, a horizontal shaft mounted in the guides, a roller on the shaft, the roller being partially immersed in the oil and projecting upwardly into the path of travel of the wheel flange, springs for yieldingly supporting the shaft and roller in this position, and means for causing the roller to rotate when it is depressed.

7. A wheel flange oiler, comprising a receptacle for oil adapted to be mounted adjacent a rail, substantially vertical guides in the receptacle, a horizontal shaft mounted in the guides, a roller on the shaft, the roller being partially immersed in the oil and projecting upwardly into the path of travel of the wheel flange, springs for yieldingly supporting the shaft and roller in this position, a series of ratchet teeth on the roller, and

a pawl mounted within the receptacle and held yieldingly in engagement with the ratchet teeth.

8. A wheel flange oiler, comprising a receptacle for oil adapted to be mounted adjacent a rail, substantially vertical guides in the receptacle, a horizontal shaft mounted in the guides, a roller on the shaft, the roller being partially immersed in the oil and projecting upwardly into the path of travel of the wheel flange, springs for yieldingly supporting the shaft and roller in this position, circular series of ratchet teeth on each side face of the roller, opposed pawls pivoted within the receptacle and each engaging one series of the ratchet teeth, and means yieldingly holding the pawls in engagement with the teeth.

9. A wheel flange oiler, comprising a receptacle for oil adapted to be mounted adjacent a rail, substantially vertical guides in the receptacle, stops at the upper ends of the guides, springs beneath the shaft normally holding same up against the stops, and a roller on the shaft which is partially immersed in the oil and projects upwardly into the path of travel of the wheel flange when the shaft is fully elevated.

10. A wheel flange oiler, comprising a receptacle for oil adapted to be mounted adjacent a rail, substantially vertical guides in the opposing sides of the receptacle, a shaft having its ends slidably mounted in these guides, means for yieldingly supporting the shaft, a roller on the shaft, and a plurality of washers on the shaft at each side of the roller to adjustably position the roller lengthwise of the shaft.

11. A wheel flange oiler, comprising a receptacle for oil adapted to be mounted adjacent a rail, substantially vertical guides in the opposing sides of the receptacle, thimbles slidable in the guides, stops at the upper ends of the guides, springs normally holding the thimbles up against the stops, a shaft rotatably mounted in the thimbles, and a roller on the shaft.

12. A wheel flange oiler, comprising a receptacle for oil shaped to fit against the vertical web of a rail and rest upon one flange of the rail base, the receptacle having projecting flanges at its ends which lie upon the rail base flange, clamping members for securing the receptacle flanges to the rail flange, and means yieldingly mounted in the receptacle and projecting upwardly at the side of the rail head into the path of travel of the wheel flange for throwing oil upwardly when depressed.

13. A wheel flange oiler, comprising an elongated receptacle for oil adapted to be mounted adjacent the side of a rail, a series of pairs of guides in the opposing sides of the receptacle, shafts rotatably mounted and adapted for substantially vertical sliding

movement in certain selected opposing pairs of the guides, means for yieldingly holding the shafts at the upper ends of the guides, and rollers mounted on the shafts and normally projecting upwardly into the path of travel of a wheel flange.

14. A wheel flange oiler comprising an elongated oil receptacle adapted to be mounted adjacent the side of a rail, a plurality

of spaced guides in the receptacle, shafts adapted to be mounted for rotation and vertically sliding movement in certain selected guides, means for yieldingly holding the shafts at the upper ends of the guides, and rollers mounted on the shafts and normally projecting upwardly into the path of travel of a wheel flange. 15
